Primary Examiner — Lauren R Calve(74) *Attorney, Agent, or Firm* — Sheridan Ross P.C.(57) **CLAIM**

The ornamental design for a pre-cast panel wall brace, as shown and described.

DESCRIPTION

FIG. 1 is a front perspective view showing the new design of a pre-cast panel wall brace;

FIG. 2 is a front elevation view of the pre-cast panel wall brace;

FIG. 3 is a rear elevation view of the pre-cast panel wall brace;

FIG. 4 is a left elevation view of the pre-cast panel wall brace;

FIG. 5 is a right elevation view of the pre-cast panel wall brace;

FIG. 6 is a top plan view of the pre-cast panel wall brace; and,

FIG. 7 is a bottom plan view of the pre-cast panel wall brace. Portions of the pre-cast panel wall brace between the break lines in the drawings form no part of the claimed design.
